UNITED STATES PATENT OFFICE.

PARMLY H. RYDER AND CHARLES W. MOORE, OF BUCYRUS, OHIO, ASSIGNEES TO
SMOKELESS OIL BURNER COMPANY, A CORPORATION OF OHIO.

OIL BURNER.

Application filed January 2, 1923. Serial No. 610,087.

The present invention relates to oil burners and more particularly is an improvement of the burner disclosed in our Patent #1,398,397, issued November 29, 1921.

- 5 An object of the invention is to provide a burner which will operate to effect a complete atomization of discharged fuel without smoking or without the precipitation of unburned fuel.
- 10 Another object is to provide a burner having the casing thereof designed to co-operate with an oil dispensing nozzle mounted therein and so disposed as to permit the utilization of the full pressure of the air supplied to the burner.

15 Another object of the invention is to provide an air valve stem with an oil passage so arranged that oil discharged from a flow control valve, may expand and the velocity thus be reduced prior to discharge from the stem.

20 A further object is to provide an outlet orifice having the wall thereof so disposed with respect to the air supply line that currents of discharged air will intersect at a point ahead of the oil discharge outlet to produce a cone shaped spray of atomized fuel.

25 A still further object of the invention is to so associate the burner and control valve that a stem element of the burner may be reciprocated without flexing the oil line.

30 Other objects and advantages will be apparent from the following description.

35 Oil burners of the type to which our invention relates may be employed to advantage in connection with various styles of heating systems such for instance, as hot air, steam or hot water.

40 The simplicity of construction and the efficient operation of our burner together with the fact that comparatively little technical skill is required to operate it, makes the burner a desirable heating element for domestic use as well as for industrial purposes.

45 The invention will be more fully understood by reference to the following description and the accompanying drawings in which,

50 Figure 1 is a longitudinal sectional view of a burner embodying our invention;

Figure 2 is a view of the discharge end of the burner; and,

Figure 3 is a fragmentary view of the

outlet of the burner with a diagrammatical illustration of the spray.

As illustrated, an oil burner constructed in accordance with our invention may comprise a casing 1 having an air chamber 2 provided with a comparatively large air inlet 3 which may be connected with a suitable air pressure line by means of an elbow or pipe 4. The casing may also be provided with an air outlet or orifice 5, which outlet may be in the form of a nozzle of frustoconical shape with the walls thereof converging toward the exterior of the casing, thus providing an outlet of gradually reducing cross sectional area. In order to obtain the maximum degree of atomization and the most efficient operation of the burner, it is important to properly taper the walls of the air outlet. We have found that a high efficiency of atomization is attained by sloping the walls of this outlet at an angle of 19 degrees; that is, a 38 degree included angle may be used.

By reason of our construction, currents of air passing from the orifice are compelled to cross at a point just ahead of the end of an oil discharge nozzle the construction and operation of which will be fully described hereinafter. The intersecting currents of air discharged from the casing pick up the discharged oil and project it in the form of a conical spray (see Figure 3) thus effecting atomization of the oil due to the rapid expansion of the air as it escapes from the chamber 2 in which the pressure may be the maximum pressure of the air supply. For the purpose of providing means for varying the air outlet area, a stem 6 is provided with a tip 7 of the same taper as the orifice. The stem 6 is provided with a threaded portion 9 disposed in a threaded aperture 11 made in a boss formed integral with the casing 1 and in axial alignment with the outlet 5. The rotation of the stem 6 about its longitudinal axis will therefore cause a change in the relative positions of the orifice 5 of the casing and the tip 7 of the stem. A lock nut 13 may be provided to secure the adjustment of the stem from accidental variation.

The tip 7 may thus be disposed in various positions along the longitudinal axis of the casing to regulate the discharge of air or may be adjusted to entirely close the outlet

when moved so as to make contact with the wall 12 of the outlet and may therefore perform the service of a valve. The provision of a valve for regulating the air outlet has considerable advantage particularly since it may be operated to permit only the required amount of air to escape from the discharge aperture of the casing. Furthermore, by virtue of a valve of the type herein contemplated the line pressure of the air may be maintained up to the point of discharge. This is an important feature as it will be evident that when a valve is disposed directly in the air line supply, the burner can only be operated at its highest efficiency when running at full capacity and under such conditions the air outlet orifice must be opened to give a maximum outlet area.

20 The use of a valve inserted directly in the air supply line for regulation purposes results in a loss of pressure due to expansion of the air within the air chamber of the burner. The effect of this reduced pressure is such that when the air is discharged through the orifice 5 it no longer has sufficient pressure to permit a maximum expansion externally of the casing and the efficiency of the burner is greatly reduced. 25 Our burner may, however, be operated efficiently when burning a minimum quantity of oil as well as when working at maximum capacity since its construction eliminates the insertion of a valve directly in the air line.

30 35 The tip 7 of the stem 6 may have a threaded end 14 which may be screwed into a threaded passage-way of a relatively large diameter and forming an oil passage 15 extending through the stem and disposed axially thereof. The end of the stem 6 opposite the tip 7 is provided with an enlarged bore 16 and an externally threaded portion 17. An adjustable connecting sleeve or nipple 18 is positioned with a head or flanged 40 45 end 19 thereof slidably fitted in the bore 16. The opposite end of the nipple 18 is threadedly connected to needle valve 21 which in turn is in communication with an oil supply pipe 22. The valve 21 may be of any 50 suitable construction, the one shown being an angle valve having a stem 23 operable by the rotation of a hand-wheel 24 to vary the position of the end 25 of the stem 23, with respect to a seat 26. Thus the supply 55 of oil admitted to the oil passage 15 may be regulated in the usual manner.

By the construction and arrangements of the parts just described it will be seen that the hollow stem 6 of the burner is reciprocable longitudinally thereof by virtue of its 60 65 adjustable association with the nipple 18 and its threaded mounting in the casing 1.

A hand wheel 27 which may be integral with a stuffing nut 28 is provided to facilitate the movement of the stem 6 when it is

desired to vary the effective area of the air outlet 5. The stuffing nut 28 has interior screw threads adapted to engage the threaded portion 17 of the stem 6, and has one of its ends terminating in an interiorly extending flange 29. A packing 30 may be inserted between the flange 29 and the adjacent end of the stem to seal the oil line from the atmosphere. A lock nut 31 may be provided to prevent relative movement of the nut 28 during a manipulation of the stem 6.

In operation, air may enter the chamber 2 of the casing from a supply line (not shown) connected with the elbow 4, the hand-wheel 27 having been turned to position the tip 7 in the desired relation to the orifice 5 to give a required air discharge. This adjustment may be made without disturbing the needle-valve 21 by reason of the 80 85 90 95 100 105 110 115 120 125 130 135 140 145 150 155 160 165 170 175 180 185 190 195 200 205 210 215 220 225 to be understood that modifications may be made therein without departing from the spirit and scope of the appended claim.

What is claimed is:

- 8 An oil burner comprising a cylindrical casing having an air inlet intermediate its ends, a tapered air outlet at one end and a threaded aperture at the other end, a stem having a tapered end complementary to said outlet and an externally threaded portion disposed in said threaded aperture, a comparatively large diameter oil passage within said stem, a valve associated with said stem to control the flow of oil therethrough, and an adjustable sealed connection between said 15 valve and stem including a tubular member having an external flange at one end slidably fitted in an enlarged bore formed in the adjacent end of said stem, said parts being held in engagement by a stuffing nut. 20

In testimony whereof, we have hereunto subscribed our names this 28th day of December 1922.

PARMLY H. RYDER.
CHAS. W. MOORE.
